(57) **CLAIM**

The ornamental design for a bioconductive tip, as shown and described.

DESCRIPTION

FIG. 1 is a perspective view of a bioconductive tip;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a perspective view thereof in an exploded assembly; and,

FIG. 9 is a perspective view thereof in use.

The broken lines in FIGS. 1–7 depict portions of the bioconductive tip that form no part of the claimed design. The remainder of the broken lines in FIGS. 8–9 depict environmental subject matter that forms no part of the claimed design.
